UNITED STATES PATENT OFFICE.

WILLIAM CHARLES STEPHENS, OF CAMBORNE, ENGLAND.

APPARATUS FOR ALLAYING DUST IN CONNECTION WITH ROCK-DRILLING MACHINERY.

SPECIFICATION forming part of Letters Patent No. 794,752, dated July 18, 1905.

Application filed May 23, 1904. Serial No. 209,423.

To all whom it may concern:

Be it known that I, WILLIAM CHARLES STEPHENS, a subject of the King of Great Britain, residing at Endsleigh, Camborne, in the county of Cornwall, England, have invented new and useful Improvements in Apparatus for Allaying Dust in Connection with Rock-Drilling Machinery, of which the following is a specification.

10 My invention relates to apparatus for allaying the dust created when drilling dry holes by percussive rock-drilling machinery, the object of my invention being to provide a simpler form of apparatus than has heretofore 15 been used for the purpose.

The apparatus constructed according to my invention comprises a spraying device attached to the air-tap of a rock-drill and provided with an adjustable nozzle for regulating 20 the quantity of water sprayed, a water-supply in connection with the said nozzle, and means for causing the ejection of the water through the spraying-nozzle, the air-supply being preferably arranged in conjunction with 25 the cock which controls the supply of air to the drill in such a manner that when the drill is started the supply of water will commence, and vice versa.

I preferably connect the spraying-nozzle 30 directly to the air-tap and arrange a suction-pipe in connection with the water-supply, so that the passage of air through the nozzle will cause water to flow through the suction-pipe, which water will be delivered with the 35 escaping air.

The suction-hose may extend to any suitable source of water, such as a bucket or other open vessel, which may be arranged below the level of the nozzle, or it may be arranged 40 above the level of the nozzle, for instance, by suspending such bucket from the tunnel-bar of the drill, so that the tendency of the water will be to run into the sprayer by gravity, and so effect a saving by the use of a smaller 45 quantity of air than would otherwise be required if the water had to be raised from a lower level.

I sometimes employ in connection with the air-pipe a two-way cock or the like so arranged 50 that when the handle is turned in one

direction the supply of air to the drill and to the ejector-nozzle will take place simultaneously and when turned in another direction air will only be admitted to the drill and not to the ejector-nozzle.

55

To enable my invention to be fully understood, I will describe the same by reference to the accompanying drawings, in which—

Figure 1 is a side elevation of a percussive rock-drill provided with the improved dust-allaying apparatus. Fig. 2 is a plan thereof. Fig. 3 is a sectional side view of the improved apparatus detached from the drill. Fig. 4 is a vertical section on the line 4-4, Fig. 3; and Fig. 5 is a sectional plan of the same. Fig. 6 is a sectional plan illustrating a slight modification.

a is the rock-drill, and *b* is the air-supply tap of the said drill.

c is the nozzle of the spraying device, the 70 said nozzle being carried by a fitting *d*, which is connected to the fitting or body *e* of the tap *b*. The said connection is advantageously in the form of a ball-and-socket joint *f*, as shown clearly in Fig. 3, so that the direction 75 of the nozzle *c*, and consequently that of the issuing spray, can be varied to a limited degree. In the arrangement shown in Figs. 1 to 5 the socket of the joint *f* is screwed into the fitting *e*, the passage *i* being of a somewhat tortuous shape. In Fig. 6, however, the said socket is formed in one with the said fitting and the passage *l* extends in a straight line from the socket to the port, with which it communicates with the plug of the tap. 80 Within the fitting *d* is a nozzle *g* adjacent to the inner end of the nozzle *c* and forming the termination of an air-passage *h*, which is a continuation of an air-passage *i* in the fitting *e*, the said latter passage terminating in a 85 port *j*, designed to coincide with a port *k*, opening into the air-port *l* in the plug *b* of the tap *b*, through which air-port the air passes to work the drill.

m is a chamber within the fitting *d* and into 90 which the nozzle *g* opens.

n is the suction hose or pipe for the water for the spraying device, the said hose being connected to a pipe *o*, opening into the chamber *m*, and advantageously provided at its 100

lower end with a strainer n' , which is placed within a suitable water-receptacle, or the strainer may be dispensed with.

The nozzle g is advantageously coned externally, and the adjacent end of the spraying-nozzle c is coned internally, as at c^o , to correspond, the said latter nozzle being rendered adjustable relatively with the former nozzle, for instance, by a screw-thread p , as shown, and provided with means for holding it in the adjusted position, suitable means comprising a blade-spring c' bearing upon one of a series of facets c^o on the nozzle c .

By the described construction it will be seen that if compressed air be allowed to flow through the nozzle g it will induce a flow of water through the hose n into the chamber m of the fitting d and drive it in the form of spray out of the nozzle c in the direction of the point of the bit of the drill, the position of the nozzle c relatively with the nozzle g being regulated by rotating the nozzle c according to the quantity of spray required in a given time. By turning the plug b' of the tap b into the position shown in Fig. 5 it will be seen that the compressed air will be supplied both to work the drill and also produce the spray from the nozzle c . By turning the said plug to a position diametrically opposite to that shown—that is to say, so that the handle b^o of the tap is in the position indicated by the dotted line 1, Fig. 2—the supply of air to the spraying device will be cut off, but that to the drill will be maintained, while by moving the handle b^o to the midway position (indicated by the dotted line 2 in the said figure) the air-supply to the drill will be cut off, but that to the spraying device maintained. By moving the handle to a point midway between the position in which it is shown and the position indicated by the dotted line 2 the supply of air both to the drill and to the spraying device will be cut off.

By forming the joint between the fittings d and e flexible, as hereinbefore described, the issuing spray can be directed to any points near the operating-bit of the drill, as desired. The said joint also allows the hose n to be turned upward, so that it can be supplied with water above the level of the nozzle c , for instance, by a bucket suspended from the tunnel-bar of the drill, so that the water will gravitate to the spraying device, and thus effect a saving of air for spraying the water as compared with that required when the water has to be raised from a point below the level of the said nozzle.

If it be required to stop the spraying device without operating the tap b , this can be effected by turning the nozzle c so as to move its conical cavity c^o into contact with the coned nozzle g , or it may be effected by the employment of a tap interposed between the main tap b and the spraying-nozzle.

My device is an improvement upon those at present in use inasmuch as I employ one hose-pipe only to convey the air to the rock-drill, as well as to the spraying-nozzle, and one hose or other pipe to be employed as a section-pipe instead of three hose-pipes, as in some of the existing devices. My apparatus is also simpler in design than any existing device inasmuch as my ejector spraying-nozzle forms part of the drill and is not a separate apparatus. Furthermore, my apparatus being part of the drill and attached to the air-cock is at all times fixed in proper alignment to project the water in the direction of the hole to be drilled.

Having now particularly described and ascertained the nature of my said invention and in what manner the same is to be performed, I declare that what I claim is—

1. In a device of the class described, the combination with a spraying device, of an air-supply tap of a rock-drill, said tap being provided with an admission-port for compressed air and independent passages to the rock-drill and spraying device and a plug in said tap constructed to admit a supply of compressed air to either or both of said passages whereby said rock-drill and said spraying device may be operated separately or together, substantially as and for the purposes described.

2. In a device of the class described, the combination with an air-supply tap of a rock-drill, of a spraying device directly connected to and supported by said tap, said tap being provided with an admission-port for compressed air and independent passages to said rock-drill and spraying device and a plug in said tap constructed to admit a supply of compressed air to either or both of said passages whereby said rock-drill and said spraying device may be operated separately or together, substantially as and for the purpose described.

3. In a device of the class described, the combination with an air-supply tap of a rock-drill, of a spraying device directly connected by a ball-and-socket joint to said tap whereby the direction of the spray may be varied, said tap being provided with an admission-port for compressed air and independent passages to the rock-drill and spraying device and a plug in said tap constructed to admit a supply of compressed air to either or both of said passages whereby said rock-drill and said spraying device may be operated separately or together, substantially as described.

4. In a device of the class described, the combination with an air-supply tap of a rock-drill, of a spraying device provided with an adjustable nozzle adapted to be rotated to regulate the quantity of spray, a blade-spring secured to said spraying device and constructed to bear upon a face of said nozzle to prevent the same from turning, said spraying device being directly connected by a ball-and-

socket joint to said tap whereby the direction of the spray may be varied, said tap being provided with an admission - port for compressed air and independent passages to the 5 rock-drill and spraying device and a plug in said tap constructed to admit a supply of compressed air to either or both of said passages

whereby said rock-drill and said spraying device may be operated separately or together, substantially as and for the purpose described. 10
